UNITED STATES PATENT OFFICE.

FREDERICK J. WARREN, OF NEWTON, MASSACHUSETTS.

BITUMINOUS STREET-PAVEMENT.

SPECIFICATION forming part of Letters Patent No. 695,422, dated March 11, 1902.

Application filed January 10, 1902. Serial No. 89,163. (No specimens.)

To all whom it may concern:

Be it known that I, FREDERICK J. WARREN, a citizen of the United States, residing at Newton, in the county of Middlesex and State of Massachusetts, have invented a new and useful Improvement in Asphalt, Bituminous Macadam, Coal-Tar, and other Bituminous Street-Pavements, of which the following is a full, clear, and exact description, reference being had to the accompanying drawings, forming a part of this specification, in explaining its nature.

The invention relates to the type of street-pavement having a wearing-section consisting of a bituminous mixture containing from four to fifteen per cent., by weight, of bitumen to eighty-five to ninety-six per cent., by weight, of mineral, such as stone, gravel, sand, clay, loam, &c. I have ascertained that the wearing-section of such pavements as now ordinarily laid have a fine cellular or honeycomb structure, sometimes visible to the naked eye and sometimes so fine as to be visible only by the aid of a magnifying-glass or a microscope.

This fine cellular or honeycomb effect is produced, I believe, because such pavements chill before their final compression to such an extent that a continuous homogeneous water and weather proof surface is not secured. However this may be, the effect of this fine cellular or honeycombed condition is to produce a crumbling of the wearing-section and a disintegration of the surface under traffic. This is due, I believe, to the fact that the cellular or honeycombed structure being open to the influences of the weather furnishes means whereby the pavement below its surface is subject to attack and disintegration by water and the circulation of air in the more or less minute cells, and I have discovered that these injurious effects of this cellular or honeycomb structure of pavement is entirely overcome by sealing the cells in such a manner as to prevent air and moisture from reaching them and circulating in them.

To so seal the cells and protect the wearing-surface of the pavement after it has been finished in the ordinary manner a thin coat of relatively pure bitumen in liquid form, sprinkled, brushed, poured, or rubbed over the sur-

face, so as to unite with it and completely close the cells thereof, and thus protect the wearing-section of the pavement from the exposure which it receives when the cells are open. 55 I have further discovered that this greatly adds to, preserves, and prolongs the life of the pavement. It also provides a cement which at the time of the application is sticky and adhesive and on which can then be 60 spread a thin coat of stone, gravel, or stone chips, which by rolling will adhere to the pavement as laid and furnish it with any desired color or roughness of surface desired. It thus becomes possible to use for such a 65 surfacing flint or other expensive but durable material, thus presenting to the wear of traffic a material which otherwise could not be economically employed.

I will now describe the invention in connection with the drawings forming a part of this specification.

Figure 1 is a view in cross vertical section of a street-pavement or roadway having the features of my invention. Fig. 2 is a view 75 in section, enlarged, representing a modification thereof. Fig. 3 is a view in vertical section, enlarged, of a portion of the wearing-section of Fig. 1.

Referring to the drawings, A represents the 80 ordinary wearing or upper section of an asphalt, bituminous macadam, coal-tar, or other form of bituminous pavement and which usually comprises a bituminous mixture of bitumen and mineral of the proportions and 85 kinds I have already indicated. This section, of the pavement is in the complete or finished form in which such pavements are now laid, and so laid it usually possesses a fine or minute cellular or honeycomb formation extending more or less through it, and which possesses a capacity for receiving and holding moisture, water, and air. The presence of moisture or air below the surface of the wearing-section tends to gradually rot it 90 and disintegrate it, so that it loses its tenacity and strength, and therefore scales and disintegrates more rapidly than it should.

It is desirable to protect the life of the upper surface of the wearing-section, and if this 100 life can be maintained in its original intensity it will withstand much longer the wear-

ing effect of traffic upon it than if it had become weakened. By sealing the cells in the wearing-section, which are in the nature of pores, the upper surface of the wearing-section becomes so protected from the injurious effects of atmospheric exposure that its life is continued and its resisting power to traffic is also continued. The pores are so fine that they cannot be shown in the drawings, and therefore cannot be lettered.

The thin coating B is of relatively pure bitumen in a liquid form, and I prefer to combine it with the surface by brushing or rubbing and so as to seal the cells and pores by a water and weather proof sealing which prevents the absorption by the pores of moisture or air or other deleterious substance from the atmosphere. This relatively pure coating when first applied to the surface of the pavement is sticky and adhesive and will act to receive and unite to the surface of the pavement a thin coat of sand, gravel, or stone chips when rolled into it, and there will then be provided the pavement not only the means for sealing its cells or pores, but also means for furnishing it with a surfacing more or less rough, as may be desired, and of any wished-for color. It also permits the application to the wearing-section of a mineral highly desirable for a wearing-surface; but it cannot be combined with a wearing-section because of expense. I refer to flint or other relatively expensive durable material.

I would state that the bituminous coating may be applied in either a hot or cold state. 35

The advantages of the invention need not further be enlarged upon.

Having thus fully described my invention, I claim and desire to secure by Letters Patent of the United States— 40

1. The application to the wearing-surface of a bituminous street-pavement having a cellular or porous character, for the purpose of closing its pores and preserving its life, of a cell or pore sealing coating of bituminous cement. 45

2. The application to the wearing-surface of a bituminous street-pavement of a thin coating of bituminous cement applied thereto in a plastic condition and combined while 50 plastic with suitable stone, gravel or sand of a character to provide a roughness to the surface of the pavement.

3. The application to the surface of a bituminous street-pavement having a cellular 55 or porous character, for the purpose of closing its pores, preserving its life and providing a wearing-surface of a more durable character than it, of a thin cell-sealing coating of bituminous cement combined and united with 60 mineral of a flinty or other hard character.

FREDERICK J. WARREN.
